ABSTRACT OF THE DISCLOSURE

A tool for tightening and locking a nut on a bolt having a substantially cylindrical body, a spindle extending axially within the body, a motor for rotating the spindle connected to one end thereof, a nut engaging wrench member connected to the other end of the spindle and also slidable axially on this end of the spindle, a pneumatically operated impact piston slidably mounted upon the spindle within the body and having a tubular sleeve projecting from its forward face for delivering an axially directed impact to the rear of the wrench member and a deforming tool mounted within the wrench member and having forwardly extending projections to engage and deform the end face of a nut which is engaged by the wrench member.

There are at present many forms of lock nuts which are adapted for application to the threaded shank of a bolt in a nut and bolt assembly. The expression "nut and bolt assembly" is intended to cover various cases where two or more members are secured together by means of a bolt, or the like, having an externally threaded shank which is engaged by a nut. Whilst in most cases the bolt will be of conventional form having a head at one end, there are also cases in which the threaded shank is in the form of a stud secured in some way in one of the members, and hence the expression "bolt" as used herein, is intended to cover also such cases.

A great many different forms of lock nuts used hitherto rely for their action upon exerting an increased gripping force on the thread of the bolt and there are various examples of nuts in which this is done by some form or other of distortion or displacement of the thread of the nut, so that at localised positions it has an increased grip on the threaded shank of the bolt such as to resist any tendency for the nut to slacken off during use when the nut and bolt assembly may be subject to vibration and other forces tending to loosen the nut.

However, even if a lock nut is used, the nut and bolt assembly is not efficient if, at the initial application, the nut is not tightened down a sufficient extent to achieve tension in the bolt shank, and it has become recognised in practice that, for maximum efficiency in bolt usage, the nut must be tightened down until a predetermined minimum tension is reached, and preferably exceeded, in the bolt shank. Unless such minimum tension is achieved during tightening then even the slightest degree of slackening of the nut may mean that all tension will disappear from the bolt shank, and although the lock nut may be perfectly efficient to resist coming completely off the end of the bolt, the position has already been reached where a bolted assembly is now no longer efficient because there is no tension in the bolt, and hence no clamping force holding the members together.

Such lock nuts, as referred to above, which act by applying an increased frictional grip, will require more "operator-torque" than a conventional nut when being used, as the operator has got to overcome the increased

2

resistance due to the locking means when tightening the nut down. This extra torque required can frequently mislead an operator into thinking that the desired torque has been achieved to get tension in the bolt shank and thus bolted assemblies can be made with such lock nuts which are not tightened to a sufficient extent to achieve maximum efficiency in the bolted connection. Also, such lock nuts are generally always more expensive than ordinary nuts.

The object of this invention is to provide new or improved apparatus for tightening a nut in a nut and bolt assembly and locking the nut on the bolt.

In one form, the apparatus may comprise a tool having a nut engaging wrench member, power means for rotating said wrench member to apply torque to a nut engaged therewith, an impact member slidable in the tool in the axial direction of the wrench member, a deforming tool associated with the wrench member and positioned to engage the end face of the nut adjacent the free end of the bolt and power means for delivering an impact to said impact member to cause it to drive the deforming tool into engagement with said end face of the nut.

In another form, the apparatus may comprise a nut-engaging wrench member, power means for rotating said wrench member, one or more impact members mounted for reciprocating movement radially of the axis of the wrench member and means for causing reciprocating movement of said impact member or members to cause it, or each one, to deliver one or more radial impacts to the wall of the nut.

In this form of apparatus there may be a nut-engaging wrench member having mounted thereon one or more impact members, each of which is mounted in the wrench member for reciprocating sliding movement in directions radially of the nut axis, a rotary driving member for rotating the wrench member to apply rotary torque to the nut, clutch means for transmitting rotary motion from said driving member to the wrench member, which clutch means is rendered inoperative when resistance to rotation of the wrench member reaches a predetermined value, and means whereby rotation of said driving member relative to said socket member causes reciprocating movement of the impact member or members.

The invention is illustrated in the accompanying diagrammatic drawings wherein:

FIGURE 1 is a part-sectioned view in side elevation of one form of tool for carrying out the invention.

FIGURE 2 is a sectioned view showing the end of the tool on enlarged scale.

FIGURE 3 is an end view looking from the right in FIGURE 2.

FIGURE 4 is a view of the end of the tool as in FIGURE 1 with a nut engaged therein prior to application to a bolt.

FIGURE 5 is a view showing the stage reached in tightening the nut prior to application of impact.

FIGURE 6 is a view showing the stage subsequent to FIGURE 5 when the impact has been delivered.

FIGURE 7 is a plan view of the nut after the locking operation has been performed.

FIGURE 8 is a section through the nut shown in FIGURE 7.

FIGURE 9 is a diagrammatic section of the operative end of another form of tool for carrying out the method according to the invention.

FIGURE 10 is an end-on view of this tool.

Referring to FIGURE 1, the tool shown therein comprises a body which is in three main parts, there being a hand grip part 10, a centre part 11, and a nose part 12, and an air motor of generally known form, and not shown, is housed within the hand grip part 10 and has a driving shaft 13 which is drivingly connected to a spindle 14

extending axially through centre part 11 and nose part 12 of the gun and at its extreme end being formed with a portion of square cross section engaging slidably in an axial passage of corresponding cross section in a sleeve 16, which sleeve is rotatably mounted within the bore of the nose part 12 and is also capable of axial sliding movement therein.

The sleeve 17 has at its forward end an axial extension 17 of reduced cross section passing rotatably and slidably through an aperture in the end wall of the nose part of the tool and there is mounted on the outer end of this part 17 a wrench member 18 which is generally in the form of a sleeve detachably secured to the part 17 by a retaining spring ring 19.

The forward free end of the wrench member 18 is provided with a nut engaging socket 20 which may be of hexagonal form or, as shown, of twelve-sided form, and within the wrench member 18, to the rear of the nut engaging socket 20, there is a recess in which is mounted the deforming tool 21 held in position by a retaining spring 22.

The construction of the deforming tool 21 is shown in more detail and described hereinafter with reference to other figures of the drawings.

The centre part 11 of the tool is of cylindrical form and provides a cylinder 23 within which there is mounted, for reciprocating sliding movement, a piston 24 formed integrally upon a tubular member 25 which is slidably mounted upon the spindle 14 and the piston 24 has a suitable sealing ring 26 engaging with the internal wall of the cylinder 23.

Mounted within the centre part 11 and fixed therein, is a block 27 having an axial opening 28 extending therethrough and of larger diameter than the diameter of the tubular sleeve 25 which therefore passes freely through the block 27 and on its forward face the block 27 is provided with a raised annular sealing lip 29 which is engaged by a resilient sealing disc 30 fixed in the rearward end of the piston 24 when this piston is in its retracted position at the right hand of the cylinder 23, as shown in FIGURE 1. Suitable sealing rings 31 are provided in the hand grip part 10 and the nose part 12 of the tool around the tubular sleeve 25 so as to seal and make airtight the space within the cylinder 23 and also the air chamber 32 to the rear of the piston 24.

Air under pressure is admitted to the air chamber 32 from a suitable supply of compressed air which would be connected by a flexible hose to the opening 33 and likewise air under pressure can be admitted into the cylinder 23 through the opening 34 also adapted to be connected to a flexible hose for supplying air under pressure, whilst with suitable and generally known form of valve mechanism, not shown, the openings 33 and 34 can also act as exhaust ports to allow air to be exhausted from the chamber 32 and cylinder 23 at the appropriate times.

Although not shown, there would also be suitable connection to supply air to, and exhaust air from the air motor in the hand grip part 10.

Also in the block 27 there is provided an exhaust port 35 communicating with an exhaust opening 36 which may be connected to a suitable tube or pipe for a purpose hereinafter referred to.

The following brief description of the operation of the tool is given with reference to FIGURE 1, although a more detailed description is given later herein with reference to FIGURES 2 to 8, which show in more detail the various stages of the operation of tightening a nut upon a bolt and locking the nut in position.

For rotating the wrench member 18 to run the nut on to the bolt and tighten it down, the air motor driving shaft 13 rotates the spindle 14 and this rotates the wrench member 18 to apply the desired torque to a nut engaged in the socket 20. When a predetermined torque has been applied, generally determined by a known form of slipping clutch,

within the tool, the air control is operated to admit air under pressure to the chamber 32 and this acts upon the face of the sealing disc 30 until the pressure builds up to sufficient value to leak past the seal between sealing lip 29 and sealing disc 30, so that instantaneously the air pressure acts upon the whole of the operative surface of the piston 24, causing rapid acceleration of the piston from right to left in FIGURE 1, thus driving the tubular sleeve 25 forwardly so that the forward end 37 of this sleeve, which acts as the impact member strikes the rear face 38 of the sleeve 16 and thereby delivers an axial impact via sleeve 16 and wrench member 18 to the deforming tool 21 to apply the desired deformation, as hereinafter described, to the nut engaged in the socket 20.

The air controls are then operated to admit air under pressure via the port 34 to the other left hand face of the piston, as seen in FIGURE 1, to move the piston back to its original position at the right hand or rear end of cylinder 23. The purpose of the exhaust port 35 is to allow escape of air from the annular chamber 39 and prevent any build-up of air pressure which might prevent the sealing disc 30 from seating firm against the cylinder 29 when the piston is in its initial position at the one end of the cylinder.

When the piston is performing its return movement the port 33 is acting as an exhaust port for exhaust of air from the chamber 32.

With reference now to FIGURE 2, the nose part of the tool body is indicated at 12, the wrench member at 18, the nut-engaging socket at 20 and the deformation tool at 21 and it will be seen that the deformation tool 21 has three equiangularly spaced projections 40 around the periphery of the axial hole 41 in the tool. This hole 41 communicates axially with a hole 42 in the part 17 and it will be seen that the forward end of the part 17 bears against an internal annular shoulder 43, in the wrench member 18, whereby the axial impact from impact member 37 is transmitted to the deformation tool 21.

Referring now to FIGURES 4, 5 and 6, there is shown the stages in the application of a nut 44 to the threaded end 45 of a bolt 46 for holding together two members 47 and 48 in a nut and bolt assembly, and this assembly has a washer 49 placed about the bolt so as to be underneath the nut when this is applied. FIGURE 4 shows the nut 44 engaged in the socket 20 of the wrench member 18 prior to application to the bolt.

The controls of the tool are operated to cause rotation of the wrench member 18, thus running the nut 44 down the threaded end 45 of the bolt until the stage of FIGURE 5 is reached when the tightening of the nut has proceeded to the extent that the torque applied by the wrench member 18 reaches a predetermined magnitude upon which the known form of slipping clutch mechanism in the tool comes into operation and rotation of the wrench member 18 ceases so that an indication is obtained that a torque of predetermined magnitude has been reached and thus the predetermined minimum tension achieved (or exceeded) in the bolt shank.

At this stage the controls of the tool are further operated to operate the impact member 37 (FIG. 1) and deliver an impact to the annular shoulder 43 of the wrench member 18 and thus to the deformation tool 21 so that this advances relative to the nut 44 and the three projections 40 form indentations in the end face of the nut (see FIG. 6) as explained more clearly hereinafter with reference to FIGURES 7 and 8.

As the effect of the impact causes the wrench member 18 and deforming tool 21 to move (in the direction left to right FIG. 6) relative to the nut 44, the end face 50 of the wrench member 18 impacts against the washer 49 and this avoids any indentation being caused on the outer surface of member 47.

To provide for this movement axially of the wrench member 18, the socket 20 is of such axial depth that when the nut is engaged therein (see FIG. 4 and FIG. 5),

the one end face of the nut projects slightly beyond the end face 50 of the wrench member 18.

Referring now to FIGURES 7 and 8, the impact of the three projections 40 of the deforming tool produce three corresponding indentations 51 in the end face of the nut 44, and as seen in FIGURE 8, these indentations deform the thread at localised positions immediately adjacent this one end face of the nut so as to force these portions of the thread radially inwards into firm frictional engagement with the thread of the bolt so as to achieve the desired locking action.

With reference now to FIGURES 9 and 10, which show diagrammatically part of another tool for carrying out the invention, the nut is shown at 110 engaged in the tool, and the form of nut preferred for use with this tool has, as shown, a generally conventional nut body 110 of hexagonal form provided at one end with an axially extending collar 111 which is of substantially reduced wall thickness and is of circular cross-section.

The tool comprises a nut-engaging wrench member 112 which has an axial opening therethrough which is of hexagonal cross-section at its forward end 113 so as to have non-rotative engagement with the hexagonal body of the nut.

The wrench member 112 is mounted concentrically within an annular body 114 which has a rearwardly axially extending part 115 which is connected to, or forms part of, the rotary driving shaft of a power-operated tool which may for example be in the form of any of the generally known types of power-operated nut runners and needs no further description.

The wrench member 112 is provided with a plurality of impact members 116, each of which is mounted slidably in a radially extending passage 117 in the wrench member, such passage 117 having an enlarged part 118 at its radially outer end in which the enlarged head 119 of the impact member slidably engages, and each enlarged part 118 having located therein a coil spring 120 acting under the head 119 to urge the impact member 116 in the radially outwards direction.

At its inner end each impact member 116 has an operative swaging end 121 of substantially conical form and when the nut is engaged in the wrench member these ends 121 are adapted to engage the reduced collar 111 of the nut.

The inner wall 122 of the annular body 114 of the driving member is formed at equi-angularly spaced positions with a number of radially inwardly projecting lobes or cam surfaces 123 and, as will be observed from FIGURE 10, each of the impact members 116 are urged by their springs 120 radially outwards so as to maintain the heads 119 of the impact members in engagement with the said inner wall 122 of the annular body of the driving member.

In the example shown, there are four impact members 116 and four cam surfaces 123.

At the front end of the tool a suitable form of retaining plate 124 is provided to hold the wrench member in position.

In operating with this form of tool, the nut engaged in the wrench member is applied to the end of the bolt and the driving member 115 rotated to run the nut along the thread of the bolt and into engagement with the abutment surface (e.g. the member 47 or washer 49 in FIG. 4). During this action the lobes 123 will be in the position indicated in FIGURE 10 and will act upon the heads of the impact members so as to form a clutch means to transmit the rotary driving torque from driving member 115 to the wrench member and thus cause rotation of the nut until such time as the torsional resistance to rotation of the nut reaches a predetermined value corresponding to a desired tension being achieved in the bolt shank, whereupon the wrench member 112 becomes stationary and the resistance of the springs 120 is overcome so that the driving member 115 continues to rotate about the axis

of the nut relative to the stationary wrench member. As will be observed from the consideration of FIGURE 10, this results in the lobes or cams 123 applying a series of radially directed impacts to the impact members 116, causing these to be driven radially inwards to operate upon the collar 11 of the nut and deform portions of the internal thread of the nut into gripping engagement with the co-operating threads of the bolt, the extent of the inwards movement of the impact members being indicated in dotted lines in FIGURE 10.

What I claim then is:

1. Apparatus for tightening and locking a nut on a bolt comprising a tool having a nut engaging wrench member, power means for rotating said wrench member to apply torque to a nut engaged therewith, an impact member slidable in the tool in the axial direction of the wrench member, a deforming tool associated with the wrench member and positioned to engage the end face of the nut adjacent the free end of the bolt and power means for delivering an impact to said impact member to cause it to drive the deforming tool into engagement with said end face of the nut.

2. A tool according to claim 1 having a body, a spindle extending axially within said body, power means within the body drivingly connected to one end of said spindle for rotating same, the other end of said spindle being drivingly connected to the wrench member for rotating same and the wrench member being slidably axially relative to said other end of the spindle, the deforming tool being connected to the wrench member and the impact member being arranged within the body of the tool so as to deliver the impact to the wrench member.

3. A tool according to claim 2 wherein the impact member comprises a piston reciprocably mounted in a cylinder formed in the tool body, the piston being slidable axially upon the said spindle and having extending from its forward face, which is the face nearest the wrench member, a tubular sleeve also slidable upon said spindle and constituting the impact member, there being suitable ports in the body of the tool for supply to, and exhaust from, the cylinder, of air under pressure for operating said piston.

4. A tool according to claim 3, in the form of a gun having a hand grip part in which is mounted an air-operated motor for rotating said spindle, a centre part which comprises the said cylinder and a forward nose part in the forward end of which there is rotatably and axially, slidably mounted a sleeve having a driving connection with the forward end of the spindle and being slidable relative thereto, the wrench member carrying the deforming tool being mounted on the forward end of said sleeve, the arrangement being that the impact member strikes the rearward end of said sleeve when the piston is operated.

5. A tool according to claim 4 wherein the wrench is in the form of a sleeve having an opening extending axially inwards from its forward end, the mouth of the opening being formed as a nut-engaging socket and the deforming tool being mounted in the said opening to the rear of said socket, said deforming tool having a plurality of forwardly extending projections adapted to deform the end face of a nut around the periphery of the threaded opening therein.

6. Apparatus for tightening and locking a nut on a bolt in the form of a tool comprising a nut-engaging wrench member, power means for rotating said wrench member, one or more impact members mounted for reciprocating movement radially of the axis of the wrench member and means for causing reciprocating movement of said impact member or members to cause it, or each one, to deliver one or more radial impacts to the wall of the nut.

7. A tool according to claim 6 comprising a nut-engaging wrench member having mounted thereon one or more

impact members, the or each of which is mounted in the wrench member for reciprocating sliding movement in directions radially of the nut axis, a rotary driving member for rotating the wrench member to apply rotary torque to the nut, clutch means for transmitting rotary motion from said driving member to the wrench member, which clutch means is rendered inoperative when resistance to rotation of the wrench member reaches a predetermined value, and means whereby rotation of said driving member relative to said socket member causes reciprocating movement of the impact member or members.

8. A tool according to claim 7 wherein the wrench member is of cylindrical form and has an axial opening therethrough, the forward end of which forms a nut-engaging socket, and the wrench member is mounted concentrically within an annular body (constituting the said driving member) having a rearwardly extending, power driven, shaft for rotating the annular body about the axis of the wrench member, the wrench member being provided with a plurality of impact members, slidably mounted in radially extending passages formed in the wrench member and the inner wall of the annular body having a plurality of inwardly projecting cam surfaces adapted to act upon the radially outward ends of the impact members to drive these radially inwardly when the annular body rotates relatively to the wrench member.

9. A tool according to claim 8 wherein each of the impact members is urged outwardly by spring means and engagement between said cam surfaces and the impact members against the resistance of the spring means constitutes the clutch means for transmitting rotary motion from the annular body to the wrench member, the resistance of the spring means being overcome when the torque applied by the wrench member to the nut reaches a predetermined value so as to permit relative rotation between the annular body and the wrench member.
